Patented Dec. 23, 1913.

UNITED STATES PATENT OFFICE.

OTTO B. HENRIKSON, OF SHELBY, MICHIGAN.

MAGNESIUM FLASH-LAMP.

1,082,326.

Specification of Letters Patent.

Patented Dec. 23, 1913.

Application filed May 1, 1912. Serial No. 694,338.

To all whom it may concern:

Be it known that I, OTTO B. HENRIKSON, a citizen of the United States, residing at Shelby, in the county of Oceana and State of Michigan, have invented new and useful Improvements in Magnesium Flash-Lamps, of which the following is a specification.

This invention relates to improvements in magnesium lamps, for taking photographic pictures by artificial light. In such apparatus, magnesium powder is blown, by the breath of the operator, through a narrow opening and in front of an alcohol flame and is there ignited. Prior forms of such apparatus have been open to the objection that when the magnesium powder became damp from the moisture contained in the breath of the operator, the slit or opening through which the powder was expelled was of such a character that the damp powder clogged it up so that the powder could not pass the opening.

The object of my invention is to provide an apparatus so constructed that such clogging cannot occur.

In the accompanying drawing, Figure 1 is a front view of the apparatus; Fig. 2 is a side view thereof; Fig. 3 is a vertical sectional view thereof.

Referring to the drawing, 1 indicates a cylindrical box or container, the lower open end of which is closed by a removable cap 2. Through the cylindrical wall of said container adjacent to said lower end passes a tube 3, around the outer end of which is passed one end of a rubber tube 4, the other end of which the operator inserts in his mouth and thus forces a blast of air into the container. In said container is magnesium powder, which, when said blast is produced, is forced into the open end of a tube 6, extending vertically within the container and out through the upper closed end thereof. The upper terminal portion of the tube 6, outside said container, is so bent, as shown at 7, that the magnesium powder, emerging therefrom, impinges against the upper concave surface of a deflector plate 8, which flares or increases in width upwardly, and is secured, as shown at 9, upon the closed upper end of the container, and passes obliquely upward through a slot 11 formed in a vertical reflector plate or shield 12, the lower end of which is secured, as shown at 13, to the closed end of the container. Said shield also widens consider-

ably from its lower portion connected with the container to the upper edge thereof. The free end of the deflector plate supports a receptacle 14 for a wick 16, for burning alcohol, which alcohol is ignited before the operation of taking a picture by means of said magnesium lamp.

The upper surface of the deflector plate is sufficiently spaced from the reflector where it passes through the slot to permit the passage, between said upper surface and reflector, of the powder and any moist masses thereof which might not be completely flattened by the deflector plate. Such masses might be formed when the lamp containing damp powder is unused for a considerable time, and the upper terminal portion of the deflector plate is substantially parallel with the reflector, and spaced therefrom not much more than the distance of the reflector plate from the upper edge of the slot. Consequently, the powder, on being forced by the blast of air through the slot and upwardly past the edge of the deflector plate near which the alcohol is burning, is immediately ignited by the flames of the alcohol. With the above apparatus there can be no possible clogging of the powder which would prevent the successful operation of the device, even though the powder be damp owing to the moisture in the operator's breath. For, on account of the cylindrical container being completely inclosed and the terminal portion of the tube 6 being in no way obstructed, the force of the operator's breath is always sufficient to produce a blast of powder through said tube 6, and this powder, on emerging from said tube, and impinging upon the concave upper surface of the deflector plate, is thereby spread into a thin sheet and therefore cannot clog up the opening between said deflector plate and the upper edge of the slot in the reflector. Again with prior magnesium lamps, it has been possible for the magnesium to become ignited within the container upon the cessation of the blast of air, when there is a tendency for the operator to draw in his breath. With the present apparatus this result is not possible, as the flame of the alcohol wick is sufficiently remote from the open end of the tube 6 to prevent the flame being drawn thereinto, and is also separated from said tube by the reflector or shield which has only a narrow slot therethrough. Another advantage of a deflector of this construction

is that the blast is kept concentrated by the continuous impact against the concave surface, so that it leaves the deflector with greater force and in a thinner sheet than is the case with previous deflectors and thereby produces a larger sheet of flame with a given amount of powder and strength of blast.

I claim:—

10. 1. A flash lamp comprising a receptacle for the powder and means for delivering a stream of powder therefrom, means for igniting the powder, a deflector for spreading the powder having a concave deflecting surface and a reflector disposed on the concave side of the deflector, the powder being delivered on to one side, and the igniting means being on the other side, of said reflector.
2. A flash lamp comprising a container for flash powder and means for delivering a stream of powder therefrom, means for producing a flame to ignite the powder, a deflector for spreading the powder and a reflector or shield disposed between the terminal portion of the deflecting surface and the orifice of the powder-delivering means, the powder orifice being on one side, and the flame being on the other side, of the reflector or shield.
30. 3. A magnesium lamp comprising a container for magnesium powder, an air conduit leading into said container, a powder conduit conducting from said container, a slotted plate, a receptacle for absorbent material and a deflector plate extending through said slotted plate and terminating closely adjacent to said receptacle.
35. 4. A magnesium lamp comprising a container for magnesium powder, an air conduit leading into said container, a powder

conduit conducting from said container, a slotted plate, a receptacle for absorbent material and a concave deflector plate extending through said slotted plate and terminating closely adjacent to said receptacle. 45

5. A magnesium lamp comprising a receptacle for magnesium powder, an air conduit leading into said receptacle, a powder conduit conducting from said receptacle, a reflector secured to the receptacle, and having 50 a slot therein, a concave deflector plate passing through said slot and a receptacle for an alcohol wick carried by the deflector plate, the deflector plate being so arranged that the powder is discharged from the powder conduit upon the deflector plate at one side of the reflector the wick being on the other side of said reflector.

6. A magnesium lamp comprising a receptacle for magnesium powder, an air conduit 60 leading into said receptacle, a powder conduit conducting from said receptacle, a flaring reflector secured to the receptacle and having a slot therein, a flaring deflector plate passing through said slot, the terminal portion of the deflector plate being substantially 65 parallel with the reflector, and a receptacle for an alcohol wick carried by the deflector plate, the deflector plate being so arranged that the powder from the powder conduit is 70 discharged upon the deflector plate at one side of the reflector, the wick being on the other side of said reflector.

In testimony whereof I have hereunto set my hand in the presence of two subscribing 75 witnesses.

OTTO B. HENRICKSON.

Correction in Letters Patent No. 1,082,326.

It is hereby certified that in Letters Patent No. 1,082,326, granted December 23, 1913, upon the application of Otto B. Henrickson, of Shelby, Michigan, for an improvement in "Magnesium Flash-Lamps," an error appears in the printed specification requiring correction as follows: Page 2, line 17, strike out the word "to"; and that the said Letters Patent should be read with this correction therein that the same may conform to the records of the case in the Patent Office.

Signed and sealed this 17th day of March, A. D., 1914.
